CAP FORMING APPARATUS

Isadore Kiwad, Westwood, N. J.

Application January 4, 1951, Serial No. 204,367

3 Claims. (Cl. 223—12)

1

This invention relates to apparatus for making articles of headwear in the nature of caps and the like.

An object of the invention is to provide a novel and improved apparatus for making headwear, such as caps and the like, in which a blank of sheet material is formed quickly and easily into a cap.

Another object of the invention is to provide a novel and improved cap making device in which means is provided for the reception and support of a cap blank of sheet material, and in which the blank is drawn and stretched over a shaping and forming die member in the presence of heat and moisture, so that the entire cap body is formed in a single operation.

A further object of the invention is to provide a novel cap making apparatus of the character described, in which, when the blank has been drawn and stretched over the die member, means is automatically applied around the perimeter of the cupped and drawn blank to draw the same inwardly against the re-entrant portions of the die, to shape the same as desired in the general and common contour of a cap.

Still another object of the invention is to provide a novel cap making apparatus of the character described, in which, upon completion of the shaping process, the various movable elements of the apparatus may be automatically returned to initial positions, ready for the next cap.

Still a further object of the invention is to provide a novel and improved cap making and forming apparatus of the character described, which is simple in design, inexpensive to manufacture, and highly efficient and rapid in operation.

These and other objects and advantages of the invention will become apparent from the following description of a preferred embodiment thereof, as illustrated in the accompanying drawings, 40 and in which:

Figure 1 is a partly sectioned elevational view of the apparatus according to the invention, showing the parts in initial elevated positions, and a cap blank sheet in position ready for commencement of the forming and shaping operation.

Figure 2 is a top plan view of the device shown in Figure 1.

Figure 3 is a partly sectioned elevational view 50 similar to that of Figure 1, except that the parts are shown in lowered positions, and the cap blank having been drawn and stretched.

Figure 4 is a sectional plan view taken on plane 55 4—4 of Figure 3.

2

Figure 5 is a fragmentary partly sectioned elevation similar to that of Figure 3, except that the draw-wire has now been drawn to further shape the cap blank.

Figure 6 is a sectional plan view taken on plane 6—6 of Figure 1.

Figure 7 is a plan view of the draw-wire, its actuating solenoids and the circuit diagram thereof.

In the manufacture of headwear, such as caps, it is of the utmost importance that all operations be performed with the highest speed, smallest requirement for use of manual labor, and automatically to the highest possible degree. The present invention provides cap forming and shaping apparatus which satisfies all these requirements, making it possible to further reduce the cost of manufacture very substantially, and to increase the rate of production of caps considerably.

In order to understand clearly the nature of the invention and the best means for carrying it out, reference may now be had to the drawings, in which like numerals denote similar parts throughout the several views.

As illustrated, there is a base member or table 10, which is relatively stationary, and may be supported upon legs, not shown, or other suitable frame members. A pair of spaced upright leg members 12 and 14 are secured to the upper surface 16 of the table 10 by means of screws or bolts 18 extending through aligned holes formed through the table 10 and foot flanges 20 and 22 integral with the leg members 12 and 14. A top wall or web 24 interconnects the upper ends of the two legs 12 and 14, and completes the formation of the U-shaped yoke member 26 which is thus relatively stationary and mounted upon the table 10. The yoke member 26 may be provided with integral ribs 28 which stiffen and strengthen the same.

A hydraulic cylinder 30 is welded to two wall members 32 and 34 the lower flanges 36 of which are secured by means of bolts 38 to the central portion of the yoke frame web member 24, with the hydraulic cylinder extending downwardly through an opening 40 in the web 24, the greater portion of the cylinder 30 extending upwards from the web. Inside the hydraulic cylinder is a piston mounted on the plunger shaft 42, for movement therewith, upwards when hydraulic fluid enters the cylinder through pipe 44, and for movement downwards when hydraulic fluid enters the cylinder through pipe 46. A motor 48 is connected to power lines through wires 50 and

52, which may be disconnected by opening switch 54 when desired. The motor 43 drives a pump 56 which is coupled thereto by shaft 58, the pump turning continuously in one direction, so that hydraulic fluid moves through the pipe 60 to the pump and moves out of the pump through pipe 62 in the directions indicated by the arrows 64. A reversing valve 66 forms a common junction for the pipes 44, 46, 60 and 62, and when the valve is in one position, pipes 62 and 46 are in communication with each other so that fluid flows from pipe 62 to pipe 46, and enters the cylinder 30 from the top, pushing the piston downwards. At the same time, the reversing valve 66 has effected communication between pipes 44 and 60, so that the hydraulic fluid can leave the cylinder below the piston and flow to the pump 56. This moves the plunger shaft 42 downwards from the position shown in Figure 1 to that shown in Figure 3, carrying with it to 20 lower position, the upper die 68, the top wall 70 of which is secured to the flange 72 of the hydraulic plunger by means of bolts 74.

Integral guide rods 76 extend upwards from the top wall of the upper die, and slide smoothly through the guide holes 78 in the yoke web wall 24, thus blocking relative turning of the upper die while movement upwards and downwards takes place, and maintaining its registry relative to the lower die. When the valve 66 is reversed, then pipes 46 and 60 are interconnected, and similarly pipes 44 and 64 are brought into communication. This causes the fluid to enter the cylinder 30 from below the piston, elevating the plunger 42 and the upper die, moving it back to original position shown in Figure 1.

The upper die has frusto-conical side walls 80 terminating at their lower end in an annular flange 82, to the undersurface of which is secured by bolts 84, the annular draw-string ring member 86 for movement therewith. It is seen that the ring member 86 has an annular groove 88 formed in its inner surface, the contour of the groove being substantially V-shaped as seen in sectional elevation in Figure 1, and a draw-wire or string 90 extends around the inside of the entire V-shaped groove so as to be normally seated therein when in extended position as shown in Figure 1. The ends 92 and 94 of this flexible wire 90 extends outwards through the two radial bores 96 and 98 respectively, of the grooved annular block or ring 86, being secured at their outer ends to the solenoid plungers 100 and 102 of the solenoid coils 104 and 106. Wires 108 and 110 connect the solenoid coils to a source of electric power, such as a battery 112, through a switch 114, so that upon closing the switch, energizing the solenoids, their plungers are then drawn in opposite directions, as seen in Figure 7, pulling with them the opposite ends of the draw wire 90, and drawing the loop formed by the wire 90 so as to make the effective diameter of the loop smaller. Upon opening the switch 114, the springs 116 and 118 pull the plungers toward each other, allowing the wire loop to be increased in diameter, and to once again seat in the V groove in the block ring 86.

A lower die 120, which is shaped to the desired contour of the cap body, or any other article which it is desired to form, is mounted on a circular base 122, which in turn is secured to the support member 124, the latter being secured to the upper surface of the table 10 so as to be relatively stationary. An annular V-shaped groove 126 is formed in the perimeter of the

base 122, to match or complement the larger V-shaped groove 88 in the upper block ring 86.

A lower annular block ring 128 having a central opening 130 is disposed below the upper block ring 86 and co-axially therewith, being mounted for vertical motion between the position shown in Figure 1 and the position shown in Figure 2, the ring 128 being in contact with the table 10 in the latter view. Rods 132 are threaded at their upper ends into recesses 134 formed in the undersurface of the ring 128 for movement therewith, and are slideable smoothly through bores 136 formed in guide posts or bearings 138. Springs 140 encircle the rods 132, and extend at their upper ends into recesses as shown, in the undersurface of the ring 128 so as to exert upward bias on the ring. At their lower ends, the springs 140 extend into enlargements 144 of the bores 136, so as to be supported thereby.

A cap blank 146 of sheet material suitable for making caps, such as felt, fabric, or other material, having been previously steamed to soften the same, is placed on the ring 128 in the position shown in Figure 1, so as to overlie the central opening of the ring. Electrical heating wires 148 or other heating means are disposed inside the lower die 120, as shown in Figure 1, to heat the same, so as to act on the cap blank 146. The valve 66 is turned so as to depress the upper die 68, the ring 86 moving downwards with it so as to resiliently grip the marginal portions of the cap blank 146 between rings 86 and 128. As the rings 86 and 128 move downwards with the upper die 68, the blank 146 is drawn and stretched around the lower die, while being subjected to heat therefrom, so as to assume the contour shown in Figure 3, the margins of the blank being drawn out from between the rings 86 and 128 in the process.

40 Then the operator closes the switch 114, energizing the solenoids 104 and 106, pulling the ends 92 and 94 of the draw wire outwardly as seen in Figures 5 and 7, making the diameter of its loop smaller, and pulling or gathering in the lower portion of the partly shaped cap blank 146. It is seen from Figure 5 that the V-shaped grooves 88 and 126 are at this point in the same horizontal plane, and the draw wire pulls the cap blank portion into the V groove 126, so as to be further shaped thereby while the heat is applied to the blank, for about three minutes.

45 The switch 114 is then opened, allowing the draw wire 90 to resume its expanded size, and the valve 66 is reversed so as to allow fluid to enter the hydraulic cylinder 30 through pipe 44, elevating the upper die 68 and allowing the ring 128 to rise also. The now shaped cap body is removed from the lower die 120, and its lower edges 150 may be trimmed off as desired, and the cap finished off by attachment of the sweatband and cap front. It will be understood of course, that the die 120 may be shaped to form the entire cap body and visor from a single blank in one operation as shown in my Patent No. 2,068,235, dated January 19, 1937, in which event the entire cap is produced even more quickly. It is seen that by molding my cap in this manner, I eliminate the need for seams and a lining, and make the cap much lighter than usual.

50 Although I have described my invention in specific terms, it will be understood that various changes may be made in size, shape, materials and arrangement without departing from the spirit and scope of the invention as claimed. It will also be understood that it is desirable to

steam and heat the blank 146 prior to the shaping operations, so as to make it soft and pliable.

I claim:

1. A cap making device comprising a table, a lower die shaped to the contour of a cap and supported on said table, the base of said lower die having a first annular groove formed in its perimeter, means for heating said lower die, and for applying moisture, a plurality of vertical bearing members carried by said table, a lower cap blank supporting ring having an opening large enough to allow said lower die to pass therethrough, and normally disposed above said lower die, rods secured to said lower cap blank supporting ring and slidably engaging said vertical bearing members for vertical movement with said lower ring relative to said table, spring means acting between said lower ring and said table to bias said lower ring in an upward direction, so that a cap blank of sheet material may be disposed on said lower ring above said lower die, a frame mounted on said table, an upper die having a downwardly open recess formed therein supported by said frame, an upper ring carried by and movable with said upper die and having a second annular recess formed in its inner surface, power actuated means on said frame for normally maintaining said upper die and upper ring in upper position, spaced from said lower die and said lower ring, and for moving said upper die and upper ring downwards into contact with said blank disposed on said lower ring, said upper die and ring being adapted during said downward motion to carry said blank and lower ring downwards, so as to draw and stretch said blank over said lower die to partially shape said blank whereby the top portion thereof assumes the contour of the upper portion of said lower die leaving a depending skirt portion and means adapted for engaging the skirt portion of said partially shaped blank for drawing the same inwards into contact with the lower portion of said lower die so as to be shaped thereby, and means for releasing said engaging means; said means adapted for engaging the skirt portion of said partially shaped blank and for drawing the same comprising a draw wire of resilient material having two ends and with its inter-

mediate portion formed into a loop which is normally seated in said second annular recess formed in said upper ring, and adapted when said upper ring is brought downwards into the same plane as said first annular groove in the base of said lower die, upon its ends being pulled in opposite directions, to resiliently constrict said loop to a smaller size, thereby drawing said skirt portion of said blank inwards to contact with said first annular groove so that said skirt portion of said blank is brought into contact with said lower contour of said lower die so as to be shaped thereby, and whereby, upon release of the pulling force on said ends of said draw wires, said draw wire loop normally resiliently enlarges again, allowing said shaped blank to be withdrawn from said lower die.

2. The construction according to claim 1 wherein electrically actuated means are provided for exerting pulls on said end of said draw wire in opposite directions to constrict said loop.

3. The construction according to claim 1 wherein said power actuated means for normally maintaining said upper die and said upper ring in upper position and moving said upper die and ring comprises the frame carried by said table, a hydraulic cylinder carried by said frame, a piston movable in said cylinder, a piston plunger movable with said piston and engaging said upper die for movement with said piston, a hydraulic pump for circulating fluid to and away from said cylinder, and valve means for admitting fluid to the cylinder above and below said piston as desired, to regulate the direction of motion thereof.

ISADORE KIWAD.
